UNITED STATES PATENT OFFICE

CHARLES C. JACOBS, OF AMBOY, ILLINOIS, ASSIGNOR TO F. C. AUSTIN
DRAINAGE EXCAVATOR COMPANY, OF CHICAGO, ILLINOIS, A COR-
PORATION OF ILLINOIS.

CLEANER FOR BUCKETS OF EXCAVATING-MACHINES.

No. 852,789.

Specification of Letters Patent.

Patented May 7, 1907.

Application filed March 10, 1906. Serial No. 305,294.

To all whom it may concern:

Be it known that I, CHARLES C. JACOBS, a citizen of the United States, residing at Amboy, in the county of Lee and State of Illinois, have invented certain new and useful Improvements in Cleaners for the Buckets of Excavating-Machines, of which the following is a specification.

My invention relates to excavating machines of that type wherein self-dumping scoops or buckets are employed; and has reference more particularly to a means for insuring the complete discharge of the contents of the bucket at its intended point of delivery.

It has been found in practice that, when operating upon certain kinds of soil, such as sticky clay, the inversion of the bucket above the intended point of delivery is insufficient to effect the complete discharge of the contents some of which tend to adhere to the bottom and rear walls of the bucket. To remedy this I have provided, in association with that part of the machine which effects or permits the inversion of the bucket, a scraper device which automatically engages the bottom wall of the bucket as the latter reaches the point of discharge and, as the bucket is inverted in the discharging operation, scrapes the bottom and rear wall thereof to an extent sufficient to detach and break up any sticky portions of the load and insure their delivery.

My invention is applicable to any excavating machine employing a reciprocating scoop and effecting the discharge of the load by a partial or complete inversion of the scoop at the end of its travel; but for convenience of illustration I have shown my improvements as applied to and embodied in a machine such as is shown in Reissue Letters Patent No. 12,441, granted to me January 30, 1906.

In the accompanying drawings, which illustrate the preferred mechanical embodiment of the invention,—Figure 1 is a side elevational view of the end portion of a bucket support and guide, showing the bucket-inverting-device and my improved cleaning device applied thereto and in the operation of scraping the rear and bottom wall of the bucket; Fig. 2 is an outer end view of Fig. 1; Fig. 3 is a top plan view partly broken

out, of the bucket guiding and supporting track; Fig. 4 is a longitudinal sectional view 55 of Fig. 1, showing the bucket partly in side elevation and just engaging the scraper or cleaner in the discharging operation; and Fig. 5 is a cross-sectional view through the bucket-supporting track, illustrating the general form and construction thereof.

Referring to the drawings, 6 designates each of a pair of parallel channel-shaped tracks, in which travel the wheels of a truck 7, in and between the side-frame members of 65 which is pivotally mounted at 8 an open-faced bucket or scoop 9 having a lower forward cutting edge 10, and a rounded or concave bottom and rear wall indicated at 11. The top of the bucket is opened, as clearly 70 shown in Fig. 2.

Secured to and depending from the end portion of the track is a bucket-inverting and discharging device comprising substantially a pair of L-shaped frames 12 secured to the 75 track members, 6, respectively. Each of these frames has substantially horizontal and vertical track-ways, 13 and 14, respectively, which correspond to the track-ways of the main track. The lower supporting rails of 80 the tracks themselves are notched at 15, which notches coincide with the inner ends of the horizontal track-ways 13 of the discharging device, as clearly shown in Fig. 4. The forward wheels of the truck are of a width 85 to drop through the notches 15, while the rear wheels are of wider tread and will ride over said notches. An operating cable 16 is attached at or near the outer end of the scoop, and passes over a guide-sheave 17 at the end 90 of the track, being led thence to a suitable winding drum (not shown). From the foregoing construction it will be seen that as the loaded bucket is drawn up the inclined track, when it reaches the point at which the forward wheels are over the notches 15, said

wheels will drop therethrough and run upon the horizontal track-way 13 of the inverting device, the rear wheels being pulled upwardly 100 past the notches, thus bringing the bucket and truck to the position indicated in Fig. 4, wherein the bucket is partially inverted, and the load partially, or it may be wholly, discharged, according as the material operated upon tends to adhere to the walls of the 105 bucket or flows freely therefrom.

Referring now more particularly to the feature or device which constitutes the principal element of the present invention, 18 designates a pair of cross-bars secured to and between the frame members of the discharging device back of the vertical track-way thereof. Secured to the cross-bars 18 and projecting inwardly across the vertical track-way 14 are a pair of arms 19, herein shown as of triangular shape, to and across the inner ends of which is secured a scraper-plate or blade 20. The lower edge of this scraper-blade is so located relatively to the path of the bottom of the scoop during the discharging operation that it engages the rear edge of the concave rear and bottom wall of the scoop during the inverting operation, in the manner clearly shown in Fig. 4; and, as the scoop is drawn still farther upwardly and outwardly, scrapes over said wall of the scoop in the manner clearly indicated in Fig. 1, the scoop being drawn nearer to a vertical inverted position, and the forward wheels of the truck, which are then the lowermost wheels, 25 being guided and confined by the vertical track-ways 14.

From the foregoing it will be seen that the action of the cleaner is to engage the load virtually at its upper end, and scrape such portions thereof as tend to adhere to the bottom wall of the scoop downwardly and out through the lower open end of the scoop, the discharging action of the scoop thus being in the same direction in which the material 35 tends to fall by gravity. The bucket having been fully discharged, the cable 16 is slackened and paid out in the opposite direction, and the upper or rear end of the truck descends, and the truck and bucket are drawn 40 back by a suitable returning cable not essential to the present invention and not herein shown.

I claim:

1. The combination with a bucket guiding and supporting track, a bucket adapted to travel thereon, and a device for effecting the inversion of the loaded bucket at a point on said track, of a stationary cleaner adapted to scrape over the bottom wall of said bucket 50 during the inverting operation, substantially as described.

2. The combination with a bucket guiding and supporting track, a bucket mounted to travel thereon, and a device for effecting the inversion of the loaded bucket at a point on

said track, of a cleaner mounted on said bucket-inverting device and adapted to automatically engage and scrape over the bottom wall of the bucket during the inverting operation, substantially as described. 60

3. The combination with a bucket guiding and supporting track, and a bucket mounted to travel thereon, of a frame suspended from said track and adapted to receive the bucket during its discharging operation and effect 65 its inversion, and a stationary cleaner mounted on said bucket-inverting frame and adapted to automatically engage the rear and bottom wall of the bucket and scrape the contents outwardly through the open forward 70 end of the bucket during the inverting operation, substantially as described.

4. The combination with an inclined bucket guiding and supporting track, a truck mounted to travel thereon, and a bucket carried by said truck, of a frame suspended from said track and having a substantially horizontal track-way communicating with said main guiding and supporting track adapted to receive and guide the forward wheels of 80 the truck, an operating cable connected to the rear end of the bucket, whereby said bucket is inverted at the end of its travel, and a scraper mounted on said suspended frame adapted to automatically engage the 85 rear and bottom wall of the bucket and scrape over the latter toward its front or cutting edge, substantially as described.

5. The combination with an inclined bucket guiding and supporting track, a truck 90 mounted to travel thereon, and a bucket carried by said truck, of a frame suspended from said track, said frame having substantially horizontal and vertical track-ways communicating with said main guiding and supporting track adapted to receive and guide the forward wheels of the truck, an operating cable connected to the rear end of the bucket, whereby said bucket is inverted at the end of its travel, and a scraper mounted on said suspended frame across the vertical track-ways 100 thereof, the operating edge of said scraper being so located as to automatically engage the upper end of the rear wall of the bucket and scrape over the latter toward the front or 105 cutting edge, substantially as described.

CHARLES C. JACOBS.
